UNITED STATES PATENT OFFICE.

ERNEST G. RAFF, OF ST. LOUIS, MISSOURI, ASSIGNOR TO LIBERTY ACCESSORIES CORPORATION, OF ST. LOUIS, MISSOURI, A CORPORATION OF MISSOURI.

EXHAUST-OPERATED WHISTLE.

1,289,540.

Specification of Letters Patent.

Patented Dec. 31, 1918.

Application filed September 10, 1917. Serial No. 190,540.

To all whom it may concern:

Be it known that I, ERNEST G. RAFF, a citizen of the United States, residing at St. Louis, Missouri, have invented a certain new and useful Improvement in Exhaust-Operated Whistles, of which the following is a full, clear, and exact description, such as will enable others skilled in the art to which it appertains to make and use the same.

10 This invention relates to whistles or signaling devices of the type that are operated by the exhaust gases of automobile engines, and has for its main object to provide a whistle which can be readily attached to the 15 exhaust manifold of the engine and which is adapted to be operated by a portion of the gases that pass through said manifold.

Another object is to provide a whistle of the character referred to which emits a soft 20 and pleasing sound, the pitch of which can be varied at the will of the operator.

Another object is to provide a whistle of the character referred to that is accessible for purposes of cleaning, repair, etc. Other 25 objects and desirable features of my invention will be hereinafter set out.

One type of so-called "exhaust horn" or whistle with which I am familiar is adapted to be arranged at the extreme rear end 30 of the exhaust pipe. This type is open to two serious objections, namely,—the fact that it is quickly rendered inefficient by accumulation of road dust and mud, and the fact that when the entire exhaust gases are 35 diverted from their usual path of travel to operate the whistle considerable back pressure is produced which materially affects the operation of the engine. Another type of whistle is adapted to be operated by the 40 compressed gases in the cylinders of the engine, but has the disadvantage of having to have finally ground and seated valves to operate against the relatively high cylinder pressure, and furthermore, gives forth a 45 shrill, unpleasant sound, due to the high operating pressure. This type also affects the efficiency of the engine, owing to the fact that whenever the whistle is operated, the compression in the particular cylinder with 50 which the whistle is connected is materially reduced.

My improved whistle is connected to the exhaust manifold of the engine in such a manner that only a portion of the exhaust gases passing through said manifold are

utilized to operate the whistle, and therefore, it will be obvious that whenever my whistle is operated the effect will be actually beneficial to the engine, in that said whistle acts virtually as a "muffler cut-out" to relieve 60 some of the back pressure that is caused by the gases passing through the muffler. The whistle comprises few simple parts on which no accurate machine work is necessary, which can be produced at a low cost of manufacture and which can be assembled and installed by unskilled labor.

Figure 1 of the drawings is a vertical sectional view of a portion of an automobile, showing the exhaust manifold of the motor 70 thereof equipped with a whistle constructed in accordance with my invention.

Fig. 2 is an enlarged longitudinal sectional view of the whistle.

Fig. 3 is a transverse sectional view, taken 75 approximately on the line 3—3 of Fig. 2; and

Fig. 4 is a detail perspective view of certain parts of the whistle disassembled.

Briefly described, my invention consists in 80 an automobile whistle provided with means controlled by the operator of the automobile for varying the pitch of the sound emitted therefrom and which is constructed in such a manner that it can be easily and quickly 85 installed on the exhaust manifold of various styles of internal combustion engines.

Referring to the drawings, which illustrate one form of my invention, A designates an internal combustion engine provided with the usual exhaust manifold B through which the discharged gases pass on their way to the muffler (not shown).

My improved whistle comprises a tube or cylinder 1 that is carried by a member 2 90 which is in communication with the interior of the exhaust manifold. In practice I prefer to construct the member 2 in the shape of an elbow, one leg of which is provided with internal threads for receiving 95 the tube 1, and the other leg being brazed or welded onto a strap 3 which is adapted to surround the manifold B. The portion of the member 2 that is welded onto said strap preferably projects through said strap and 100 is adapted to pass through a hole 4 formed in the manifold B when the whistle is in operative position, said strap being preferably formed of resilient metal so that the same 105 can be drawn up tightly by means of a bolt 110

5 that passes through ears 6 on the under-side thereof, thus clamping the whistle tightly in position on said exhaust manifold. If desired, suitable packing may be interposed between the strap 3 and the manifold B adjacent the hole 4, so as to preclude the possibility of the exhaust gases leaking at this point, but this is not essential to the successful operation of my invention. I also 10 wish it to be understood that my invention is not limited to the precise method just described for connecting the member 2 to the exhaust manifold B, as said connection could be made in various other ways without departing from the spirit of my invention. It 15 is obvious that on different types of engines different methods of installing the whistle would be required, but it is not here deemed necessary to go into details as to the various 20 obvious modifications which would present themselves. The whistle proper comprises a plug 7 that is inserted in the inner end of the cylinder 1 and secured thereto by any suitable means, such as a cross pin 8, as 25 shown in Fig. 4, said plug being provided with a flat spot or cut away portion 9 which allows a portion of the gases in the manifold B to escape into the cylinder 1 under certain conditions, to be hereinafter 30 described. A piston valve or cylindrical plunger 10 slidably mounted in the cylinder 1 normally bears against the plug 7 under the influence of a coiled expansion spring 11 that is arranged between one end of said plunger 35 and an abutment 12 that is threaded into the outer end of the cylinder 1, as shown in Fig. 2. When the plunger 10 is in its normal position, as indicated by dotted lines in Fig. 2, it serves to prevent the gases in the 40 manifold B from escaping through the cut away part of the plug 7 into the cylinder 1, and also closes an aperture 13 cut in the tube 1 adjacent the inner end thereof, as shown clearly in Fig. 2. An operating cable or 45 cord 14 is secured to the plunger 10 in any suitable manner, such as by means of the eye 15, and said cord passes through an opening 16 in the abutment 12 and leads to a point within convenient reach of the operator of the car. 50

When the cord 14 is pulled by the operator in a direction to compress the spring 11, the piston valve or plunger uncovers the cut away portion 9 of the plug 7 and allows 55 a portion of the gases to pass therethrough into the cylinder 1 from which they escape through the aperture 13 and produce a musical whistling sound. By moving the plunger 10 toward or away from the plug 7, the 60 pitch of the sound emitted from the aperture 13 can be varied at will, and when the operator releases the cord 14, the plunger 10 will, under the influence of the spring 11, return to the dotted line position shown in 65 Fig. 2 of the drawings, and thus automatically

prevent the exhaust gases from acting on the sound producing means of the whistle.

In practice I prefer to arrange the operating end of the cable or cord 14 adjacent the steering wheel of the automobile and to have said cord pass through suitable pulleys or eyelets 17 arranged in the dash of the automobile, but the particular manner of leading the operating cable to within convenient reach of the driver of the automobile 75 can be varied at will.

In the drawings forming part of this specification I have shown the whistle as being arranged in a substantially horizontal position on the exhaust manifold, but it 80 is obvious that said whistle could be arranged in a vertical or an inclined position without changing the mode or result of operation.

From the foregoing it will be seen that I 85 have devised a whistle for automobile engines that is easily accessible for purposes of cleaning, repair, etc.; that is not exposed to road dust and mud; that will emit a pleasing musical sound, not a shrill siren whistle, 90 owing to the fact that it is operated by the gases in the exhaust manifold which are of only a few pounds pressure; a whistle in which the pitch of the sound emitted therefrom can be varied at the will of the operator; that comprises few simple parts that can be manufactured cheaply and which can be readily installed on the exhaust manifold of an automobile engine by simply drilling a 95 hole in the manifold at any accessible point and clamping the supporting strap around the same.

Having thus described my invention, what I claim, and desire to secure by Letters Patent, is:

1. In a signaling device adapted to be operated by the exhaust gases in the exhaust pipe of an internal combustion engine in advance of the muffler, a hollow member that projects through an opening formed in said pipe, a clamping ring secured to said member and adapted to encircle said pipe and be clamped thereto whereby said member is held in place on said pipe, and an audible signal secured to said hollow member. 110

2. In a signaling device adapted to be operated by the exhaust gases in the exhaust pipe of an internal combustion engine, a hollow member mounted on said pipe between the engine and a muffler, a flange surrounding said member intermediate its ends whereby the lower portion of the member may project through and be suspended in said pipe, a band connected to said member constructed to surround said pipe and means 115 to rigidly secure said band to said pipe and an audible signal connected to the other end of said member.

3. In a signaling device adapted to be operated by the exhaust gases in the exhaust 120

pipe of an internal combustion engine, a hollow member mounted on said pipe between the engine and a muffler, a flange surrounding said member intermediate its ends 5 whereby the lower portion of the member may project through and be suspended in said pipe, a band connected to said member constructed to surround said pipe and means to rigidly secure said band to said pipe, and 10 an audible signal connected to the other end of said member, a plug secured in the upper end of said member with a port between it and said member, a tube secured to the upper end of said member and having a port, a manually controlled plunger in said tube 15 adapted to close said port and said opening of the tube; said plunger also being adapted to vary the pitch of the signal as it is moved toward or away from said port and opening.

ERNEST G. RAFF.
